UNITED STATES PATENT OFFICE.

ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

METHOD OF MAKING FULCRUMS.

Application filed March 20, 1920. Serial No. 367,367.

To all whom it may concern:

Be it known that I, ARMAND H. PEYCKE, a citizen of the United States, residing at Chicago, in the county of Cook and State of Illinois, have invented certain new and useful Improvements in Methods of Making Fulcrums, of which the following is a specification.

This invention relates to a method of 10 making fulcrums.

The object of the invention is to simplify and improve the method of making brake beam fulcrums.

This and other objects are accomplished 15 by means of the method disclosed on the accompanying sheets of drawings, in which—

Figure 1 is a sectional view of a drag and cope showing the lever member disclosed in Figure 5 as a core, there being other cores supplied, around which molten metal is 20 poured for forming the strut;

Figure 2 is a sectional view of the same arrangement taken at right angles to that shown in Figure 1;

Figures 3 and 4 are sectional views taken in the planes of lines 3—3 and 4—4 of Figure 2;

Figure 5 is the lever supporting member which acts as a core in my method, and 30 which may be formed by forging or casting; and

Figures 6 and 7 are different plan views of the completed fulcrum.

The various novel features of the invention will be apparent from the following description and drawings, and will be particularly pointed out in the appended claim.

Referring first to Figure 5, it will be noted that I have shown a blank or lever 40 supporting member 10, having a slot 11 for the reception of the brake lever, the ends of the member 10 being provided with trunnions 12 and 13, whereby the lever supporting member 10 may be rotated in the strut proper for making the fulcrum reversible. The trunnion members 12 and 13 are provided with hollow portions 14 and 15 respectively; and the trunnion portion 13 is provided with a keyway 16 for locking the rotatable lever supporting member 10 in operative position.

After the blank or lever supporting mem-

ber 10 is formed, either by casting or forging as mentioned hereinabove, the surfaces of said lever supporting member 10 are 55 coated with shellac or any other material which forms a good parting medium, or which prevents adhesion of molten metal. This lever supporting member 10 is then placed within a drag 17 and cope 18 with 60 the associated cores set in place. As a matter of fact, the lever supporting member 10 acts as a core itself. A key core 19 is inserted in the trunnion end 13 of the member 10 and is associated with a core 20, by means 65 of which a band 21 is formed for the reception of the compression member of the brake beam. Another core 22 extends through transverse openings 23 in the lever supporting member 10 to prevent the said pivot pin 70 openings 23 from being filled with metal. The remaining core 24 is placed within the trunnion 12.

After all of the surfaces of the cores are properly treated with the parting medium, 75 the molten metal is poured into the mold for forming the strut 25 around the lever supporting member 10, encasing same, the completed fulcrum being shown in Figures 6 and 7. It will be understood that after the 80 fulcrum is completely formed, the sand cores 19, 20, 22 and 24 will be forced away from the metal parts.

As shown in Figures 6 and 7, the strut is provided with a seat 26 to receive the tension 85 rod of the brake beam, and with a banded portion 21 to receive the compression member of the brake beam. A key 27 is provided for holding the lever supporting member 10 in operative position. The openings 90 28 formed in the sides of the strut are for the passage of the pin which pivotally connects the brake lever and the lever supporting member 10. The pin forms no part of this invention, but it may be stated that it is 95 held in place within the lever supporting member 10 by any suitable cotter, of which the head and leg extremities are received in grooves 29 and 30 in the member 10.

It is my intention to cover all modifications of the invention falling within the spirit and scope of the following claim.

I claim:

The method of making a fulcrum member

of the kind in which a brake lever supporting member is revolubly encased within a strut, which method consists in mounting said brake lever supporting member in a mold, mounting removable cores upon said brake lever supporting member whereby said brake lever supporting member and

cores provide a compound core, pouring metal around said compound core to form a strut, and removing said removable cores to provide apertures for said fulerum.

Signed at Chicago, Illinois, this 27th day of February, 1920.

ARMAND H. PEYCKE.
